Primary Examiner—Nelson C. Holtje**Assistant Examiner—Martha Thompson****Attorney, Agent, or Firm—Milton S. Gerstein****[57]****CLAIM**

The ornamental design for a combined note holder clip and reminder light, as shown and described.

DESCRIPTION

FIG. 1 is a front elevational view of a combined note holder clip and reminder light showing my new design;

FIG. 2 is a rear elevational view;

FIG. 3 is a side elevational view;

FIG. 4 is a bottom plan view;

FIG. 5 is a top plan view; and,

FIG. 6 is a perspective view thereof.

The paper fragment depicted by means of broken lines in FIG. 3 has been shown for illustrative purposes only and forms no part of the claimed design.
